UNITED STATES PATENT OFFICE.

JOHN L. NILSON AND JOHN PRINCE, OF CHICAGO, ILLINOIS.

PRESSURE-GAGE.

1,274,579.

Specification of Letters Patent.

Patented Aug. 6, 1918.

Application filed January 29, 1917. Serial No. 145,054.

To all whom it may concern:

Be it known that we, JOHN L. NILSON and JOHN PRINCE, citizens of the United States, residing at Chicago, in the county of Cook and State of Illinois, have invented certain new and useful Improvements in Pressure-Gages, of which the following is a specification.

Our invention relates to pressure gages and has particular reference to air-pressure gages adapted to be interposed between the ends of and in an air tube to register the degree of pressure between its source and where it is applied, as in connection with automobile and bicycle pumps.

The general objects of the present invention are to reduce the amount of material now required for the manufacture of these devices; to simplify construction; to lighten the weight; to make more compact for tool-box storing purposes; to strengthen the construction; to arrange for a construction which gives a protected position of the gage in the tool-box; to position the gage on the air-tube, in which it is interposed as a section, so as to make it more conveniently readable to the operator of the air pump; to make more convenient the crimping of the air-tube ends, or the ferrules thereon, to the nipple ends; to reduce the length and work of boring of the latter; to cause the air-tube ends to act as stops which hold the body of the casing and its cap or cover together, and to provide such other improvements incidental to the general construction and arrangement as will hereinafter appear from the subjoined description, the accompanying drawings and the appended claims.

The present invention therefore consists in the novel construction, combination and arrangement of parts, all as hereinafter described in detail, illustrated in the accompanying drawing, and more particularly pointed out in the appended claims.

45 In the drawing—

Figure 1 is a perspective view of our improved gage interposed in a section of air-tube, and showing its readable position to a hand-pump operator, as well as the body and cover holding means for the case provided by our improved arrangement of the abutting tube-ends.

Fig. 2 is a vertical section of Fig. 1, including the tube and gage.

55 Fig. 3 is a section taken substantially on line 3—3 of Fig. 2.

Fig. 4 is a perspective view showing the improved connection of nipple, or nipples, or nipple-ends, with the hollow gage spring of the "Bourdon" type of pressure gage, 60 which places the nipple portion of the air-passage, or the air-tube, within the circle of the periphery of the gage case to preserve its integrity and strength, and in attainment of other enumerated objects of this invention. 65

Referring in detail to the several views, the leading feature of this invention which distinguishes it from the various forms of this type of gage, as well shown in Fig. 4, 70 is the elimination of some metal, intermediate and space-occupying parts, and intermediate borings or passages between the metal tube, or double-ended nipple. Fig. 4 also shows the bearing-arm for the pointer 75

In the several views 2 represents the body of the usual form of cylindrical casing provided with the usual cover, or cap, 3; 4 is a nipple with grooved ends 5 and 6 to which 80 are attached flexible air-tube sections 7 and 8 ordinarily fastened by ferrules 9 and 10 that are crimped onto the tube ends, the improved accessibility for the crimping tool or instrument being also a feature of the 85 present improvement. Preferably as substantially an integral part of the nipple 4 is a bearing arm 11 having an apertured bearing portion 12 for a spindle 13 carrying a pointer 14 which traverses graduations 15 on a semi-circular dial 16 that is fastened by a single screw that has threaded engagement with an apertured hub 18 which forms the terminus of the arm 11. This arm 11 may be soldered onto the part 4, 90 cast integral therewith, or made a part thereof by any of the well known means available to manufacturers. To the middle portion of the nipple 4 is attached at right angles the inlet end of the usual hollow and 95 curved gage spring 19 on the free end of which is an apertured lug 20 that is pivoted to one end of a link 21, the other end of which is pivoted at 22 to the free end of an elbow 23 on the pointer 14. Like the arm 100 11 the spring 19 may be attached to the part 4 by any of the well known means, such as soldering or brazing. The bore 24 of the nipple is in communication with the bore 25 of the gage spring to the free end 110 of which movement is imparted through air or fluid pressure in the space 25 tending to

straighten out the spring. In the cover or cap 3 is a substantially crescent-shaped opening 26 that is closed by a transparent substance such as glass, mica or celluloid 27 which is riveted to, or otherwise secured to the cover top by a fastener 28. The body 2 of the casing is secured to the arm 11 by means of screws 29 and 30 which engage screw holes in the bottom of the casing and 10 thread holes in the under side of the arm 11. In the prevailing forms of construction,—modified in numerous ways,—adapted for the present general purpose, as distinguished from terminal gages which register pressure at the point where it is applied, the double-ended nipple 4 is arranged outside of the casing 2 and is provided with a branch or coupling with a by-pass therein. This branch occupies, substantially, the position 15 of the bearing arm 11 in the present invention, enters through an opening in the periphery of the casing, and is provided with more or less complicated, expensive and difficult to make connections with the outlet 20 25 end of the passage 25 in the gage spring, shown in Fig. 3 in section which exposes the said passage. In such prevailing forms of construction the nipple 4 also occupies a position at right angles to its position here- 30 in shown, that is, its long axis is parallel to the plane of the dial, which places the dial on edge, instead of face upward, as in Figs. 1 and 2, and makes the reading of the 35 gage inconvenient and awkward. On the other hand such construction places the easily breakable face or sight portion of the gage either up or down in the tool-box when the flexible tube 7 and 8 is coiled into said box, in which position the weight of 40 other tools in the box often cause damage to the gage. In the present construction when the air tube is coiled around the gage, it is automatically placed on edge in the tool box, when the coiled tube is laid flat 45 or tends to assume that position. The old forms of construction of gages for this purpose generally sever the circular or peripheral band portion of the casing 2. When the nipple 4 extends tangentially from the 50 circular side of the casing 2, it elongates the nipple. This requires more room, material and labor in boring. A projection of the T connection which enters the casing far beyond the edge of the casing makes 55 the gage and its nipple undesirably bulky, heavy and expensive in the amount of material used. Such lengthening or projection

of the nipple is in such construction necessary to avoid the cramped and substantially wedge-shaped spaces between the straight 6 nipple and the circular casing side into which the tube ends could not be entered, or crimped. As shown in Figs. 1 and 2, by placing the ferrules 9 and 10 against the top and bottom of the casing free accessibility for the attachment of the tube sections 7 and 8, and for crimping the ferrules thereon, is provided. The ferrules are also caused to serve as means for locking the casing body and its cover together against accidental separation. Only to the extent of the comparatively small depth of the casing 2 is the entire length of the nipple 4 made unavailable for engagement with the air-tube sections. This permits the use of 75 a considerably shorter nipple than where it must cross the diameter of the casing or be positioned tangentially to its rim,—an important saving in an article sold at, say, in the neighborhood of a quarter of a dollar 80 apiece.

Having thus described our invention, we claim as new and desire to secure by Letters Patent—

1. The combination in a gage of the class 85 described, of a nipple which extends through the body of the gage and has thereon a bearing arm which extends at right angles from the body of the nipple to which the dial and the body of the casing are attached, said 90 nipple being arranged perpendicularly to the face or dial of said gage.
2. The combination in a gage, of a gage spring, a nipple that has an opening there- 95 through which extends to opposite sides of the gage body, said opening leading to the opening in the gage spring, and air-tube sections arranged to abut against the bottom and cover of the gage casing and hold said cover in position on the body of the 100 casing.
3. The combination in a gage of the class described and its spring and casing, of a nipple having hose or tube-engaging ends 105 projecting from, respectively, the top and bottom of said casing, and an intermediate portion which connects directly with the gage spring and supports the body of the casing and its mechanism on said nipple.

In testimony whereof we have hereunto signed our names.

JOHN L. NILSON.
JOHN PRINCE.
